CLAIM

We claim the ornamental design for a package actuator, as shown and described.

DESCRIPTION

FIG. 1 is a rear perspective view of a package actuator of the present invention.

FIG. 2 is a front view of the package actuator depicted in FIG. 1.

FIG. 3 is a left side view of the package actuator depicted in FIG. 1, the right side being a mirror image

FIG. 4 is a rear view of the package actuator depicted in FIG. 1.

FIG. 5 is a top view of the package actuator depicted in FIG. 1; and,

(Continued)

FIG. 6 is a bottom view of the package actuator depicted in FIG. 1.

The broken lines are shown for the purpose of illustrating environmental subject matter and parts of the article that form no part of the claim.
